(57) **CLAIM**

The ornamental design for a trim molding for a motor vehicle window, as shown and described.

DESCRIPTION

FIG. 1 is a perspective view of a trim molding for a motor vehicle window, showing my new design, with a middle portion broken away to indicate no particular length; and, FIG. 2 is an end view thereof, the opposite end view being a mirror image.

The broken lines in FIG. 2 show a window edge portion and form no part of the claimed design.
